FLUID PRESSURE MOTOR WITH PISTON
ACTUATED PILOT CONTROL MEANS

Fred E. Cooper, Gardena, Calif.

Application March 20, 1947, Serial No. 736,006

2 Claims. (Cl. 121—157)

1

This invention relates to fluid-pressure motors of the multi-cylinder type, and it is an improvement on my fluid pressure motor disclosed in my United States Letters Patent No. 2,397,778, issued April 2, 1946.

The general object of the invention is to provide an improved fluid-pressure motor, particularly useful for operating an oil well pump, which is enclosed within a housing suspended in an oil well, to one end of which housing is connected an oil well pump operated by the motor and to the other end of which housing is connected a discharge pipe for discharging the oil pumped by said pump from the well through said housing.

Another object is to provide an improved fluid-pressure motor, including a plurality of pump units, connected in line, for operating an oil well pump or other mechanism.

A more particular object is to provide an improved fluid-pressure motor controlled by a pilot-valve mechanism.

Other objects and advantages will appear hereinafter as this specification progresses.

The invention is illustrated in the annexed drawings, which form a part of this specification and in which:

Fig. 1 is a longitudinal section of my invention shown within an oil well casing, and connected to an oil-well pump in said casing, below the oil level of the well in which said casing is located.

Fig. 2 is a longitudinal section of my invention, taken on line 2—2 of Fig. 3, with its piston shown in position at the upper end of its stroke.

Fig. 3 is a longitudinal section of my invention, taken on line 3—3 of Fig. 2.

Fig. 4 is a longitudinal section of my invention taken on line 4—4 of Fig. 3, showing the valve head partly broken away and illustrating the valve ports in said head.

Fig. 5 is a bottom plan view of the valve head.

Fig. 6 is a plan view of the valve mechanism of my invention.

Fig. 7 is a side elevation of the valve mechanism of my invention with certain valve parts removed and showing certain valve ports.

Fig. 8 is a longitudinal section of my invention like Fig. 3, but with its piston shown at the lower end of its stroke.

Fig. 9 is a longitudinal section of my inven-

tion shown in multiple of two cylinder and piston units.

Referring more particularly to the drawings, in which corresponding parts are designated by the same reference numerals in all of the figures, 1 designates a valve housing, which is closed at its upper end by an upper end wall 2, and open at its lower end. A fluid intake pipe 3 is threaded at its lower end, at 4, in said upper end wall 2 of said housing 1 for conducting fluid under pressure, such as compressed air or gas into the upper end of said housing. A fluid exhaust pipe 5 extends through a packing box 6 in said upper end wall 2 of said housing 1. The lower open end of the housing 1 is formed with an internal thread 7 which is engaged by an external thread 8 on the lower end portion of a valve head 9 for detachably securing said valve head in said housing at one side thereof, as clearly shown in Fig. 3. On the upper end of the valve head 9 is formed a cylinder 10 in which reciprocates a piston 11, from which a piston rod 12 extends downwardly through a packing box 13 in the lower head 14 of said cylinder, and to the lower end of said piston rod is connected a main slide valve 15 which slides on the longitudinally extending valve face 16 of the valve head 9. In the lower end of the valve head 9 is formed a coupling socket 17 with an internal thread 18, in which socket is fitted the upper end of a connecting tube 19 formed at said end with an external thread 20 which engages said internal thread 18 in said socket 17, whereby said tube 19 is detachably coupled to the lower end of the valve head 9. The valve head 9 is formed with a plurality of fluid ports 21, 22, 23, 24, and 25. The port 21 extends longitudinally in the valve head 9 with one end thereof extending through the upper end of said valve head and its lower end extending outwardly through the valve face 16 of said valve head as indicated at 26. A pipe 27 connects the upper end of the port 21 and the lower end of the cylinder 10. The port 22 extends longitudinally in the valve head 9 with its upper end extending through the valve face 16 of said valve head at 28, and with its lower end extending through the lower end of said valve head into the coupling socket 17, and the upper end of the tube 19. The port 23 extends longitudinally in the valve head 9 with its upper end 45 extending through the upper end of said valve

head and its lower end extending through the valve face 16 of said valve head at 29, there being a pipe 33 connecting the upper end of said port 23 and the upper end of the cylinder 10. The port 24 extends longitudinally in the valve head 9, with its upper end extending through the upper end of said head, and its lower end 31 and a branch 32, intermediate the ends of said port, extending through the valve face 16, the upper end of said port 24 being connected to the lower end of the exhaust pipe 5 by a screw coupling 33, threaded in the upper end of the valve head 9. The port 25 extends longitudinally in the valve head 9, with its upper end 34 extending through the valve face 16 and its lower end 34' extending downwardly through the lower end of said valve head through the annular wall of the coupling socket 17 outside of said socket and the tube 19, as shown in Fig. 3.

A pilot slide valve 35 is secured on the upper end of a reciprocative valve rod 36 in sliding contact with the valve face 16 of the valve head 9, which valve rod 36 extends downwardly through a lower end wall 37 of the valve head 9 above the socket 17 and through a packing box 38 in said wall into said socket and the tube 19, which wall extends laterally from the valve face 16 of said valve head 9 and is a part of the lower end portion of said head. On the lower end of the reciprocative valve rod 36 is secured a collar 39 and an arm 40 extends laterally from said rod at a pre-determined distance above said collar, for the purpose hereinafter more fully described.

On the lower end of the connecting tube 19 is formed an external thread 41 and a cylinder 42 is formed in its upper end with an internal thread 43, which thread is screwed on the said external thread 41 on the lower end of said connecting tube, whereby said cylinder is detachably connected at its upper end to the lower end of said connecting tube. In said cylinder 42 is slidably fitted a piston 44 secured on a tubular piston rod 45 intermediate the ends of said piston rod, on the upper end of which rod is threaded an abutment nut 46 which is locked in adjusted position by a lock nut 46'. The cylinder 42 is formed near its upper end with a head 47 through which the piston rod 45 extends upwardly from the piston 44 into the connecting tube 19 through the collar 39 on the lower end of the valve rod 36 and under the arm 40 on said valve rod, there being a packing box 47' in said head 47 fitted around said piston rod. The lower end of the cylinder 42 is formed with an external thread 48, and a lower end head 49 is formed with an upstanding annular flange 50 which has an internal thread 51 screwed on said cylinder end thread 48, whereby said head is detachably secured on the lower end of said cylinder 42. The tubular piston rod 45 extends downwardly from the piston 44 through said lower end head 49 of the cylinder 42, there being a packing box 52 in said cylinder head fitted around said piston rod 45, and said tubular piston rod is provided with a port 53 extending through its wall below the piston 44. The cylinder 42 is provided with a port 54 leading into and through the upper end of its wall into the upper end of said cylinder and the upper and outer end of which port and the lower and outer end of the valve port 25 are connected by a pipe 55.

The parts above described including the housing 4, connecting tube 19 and cylinder 42, and the parts contained therein constitute my fluid-pressure motor, designated in its entirety as 56, which is enclosed within a motor chamber 57. Said

motor chamber is closed at its upper end by an upper end wall 58 and is formed at its lower end with a reduced tubular extension 59 which is open at its lower end and is formed with an external thread 60. An oil pump 61, including a pump barrel 62, a piston 63, an inlet valve 64 and an outlet valve 65 in said piston, is detachably coupled at its upper end to the lower end of the motor chamber 57, by engagement of an internal thread 66 in the upper end of said pump barrel, with the external thread 60 on the lower end extension 59 of said motor chamber. The upper end of the piston 63 is connected to the lower end of the piston rod 45 of my fluid-pressure motor 56 by a connecting rod 67, which extends through the lower end extension 59 of the motor chamber 57, the lower end of said rod being coupled by a screw coupling 68 to the upper end of the cage 69 of the outlet valve 65 on the upper end of the piston 63, and the upper end of said connecting rod 67 being coupled to the lower end of said piston rod 45 by a screw coupling 70. An outlet pipe 71 leads upwardly from the upper end of the motor chamber 57 and is screw seated at its lower end at 72 in the upper end wall 58 of said chamber.

The fluid-intake pipe 3 and the fluid-exhaust pipe 5 of my fluid-pressure motor 56 extend upwardly from the upper end of the valve housing 1 of said motor through the upper end wall 58 of the motor chamber 57, and said intake pipe 3 and said exhaust pipe 5 are threaded in said end wall 58 of said chamber at 73 and 74, respectively, whereby my fluid-pressure motor 56 is suspended in operative relation in the motor chamber 57, with the lower end of its cylinder 42 elevated slightly above the lower end wall 75 of said motor chamber, from which end wall depends the tubular extension 59, providing a space 76 between said lower end wall and said lower end of said cylinder, which space leads from the upper end of said tubular extension 59 to the vertical space 77 between my fluid-pressure motor 56 and the vertical wall of the motor chamber 57.

The outlet pipe 71 and the intake pipe 3 and exhaust pipe 5 being threaded and secured at their lower ends in the upper end wall 58 of the motor chamber, extend upwardly in the well casing 78, in the lower part of which my fluid-pressure motor 56 and the oil pump 61 are located, and the upper ends of said pipes extend through and are secured in a casing head (not shown) at the upper end of said casing 78, whereby said motor and pump are suspended in operative position in the lower part of said casing and the oil well lined by said casing.

The operation of my invention is as follows:

Assuming the parts to be in the position as shown in Figs. 1, 2 and 7, fluid under pressure, such as air or petroleum gas, is introduced through the intake pipe 3 into the upper end of the valve housing 1 and fills said housing, whereupon said fluid enters the upper end 34 of the port 25 and passes downwardly through said port, pipe 53 and port 54 into the upper end of the cylinder 42 above the piston 44, and forces said piston, piston rod 45, connecting rod 67 and the pump piston 63 downwardly, and the fluid below the piston 44 is forced by said piston through the port 53, tubular piston rod 45, connecting tube 19, port 22, main valve 15, branch 32 of exhaust port 24 and said exhaust port and exhaust pipe 5, until the abutment nut 46, on the upper end of the downwardly moving piston rod 45 engages the collar 39 on the lower end of the valve operating rod 36 and moves said rod and the pilot

slide valve 35 down until said valve uncovers the lower end 26 of the port 21 and covers the lower end 29 of the port 23, and the lower end 31 of the port 24, whereupon fluid under pressure enters the lower end 26 of the port 21 and, passing upwardly through said port into the lower end of the pilot cylinder 10, forces the piston 11, piston rod 12 and main slide valve 15 upwardly, while the fluid in the pilot cylinder 10 above said piston 11 passes out through the pipe 30, port 23, pilot slide valve 35, exhaust port 24 and exhaust pipe 5, until said upwardly-moving main slide valve 15 uncovers the end 28 of the port 22 and covers the end 32 of the exhaust port 24, and the end 34 of the port 25, whereupon fluid under pressure passes from the housing 1 into the end 28 of port 22, through said port into the connecting tube 19 and into the upper end of and downwardly through the tubular piston rod 45 and out of said tubular rod through port 53 into the lower end of the cylinder 42 under the piston 44. Said fluid under pressure in the lower end of the cylinder 42 under the piston 44 forces said piston and piston rod 45 and the pump piston 63 upwardly and the fluid above the piston 44 out of the upper end of the cylinder 42 through the port 54, pipe 55, port 25, main slide valve 15, branch 32 of exhaust port 24 and through said exhaust port and the exhaust pipe 5, until the upper end of the upwardly-moving piston rod 45 engages the arm 40 and moves said arm and the valve-operating rod 36 and pilot slide valve 35 upwardly, until said valve uncovers the end 29 of the port 23 and covers the end 26 of port 22 and the end 31 of port 24, whereupon fluid under pressure passes from the cylinder 1 into the end 29 of port 23 and through said port and pipe 30 into the upper end of the pilot cylinder 10, and said fluid forces the piston 11, piston rod 12 and main slide valve 15 down, until said valve uncovers the end 34 of the port 25, and covers the ends 28 and 32 of the port 22 and exhaust port 24, respectively, thus bringing the parts of my fluid-pressure motor back to their initial position, after completion of a cycle of operations of my motor, whereupon the above described operations of my motor are repeated, and during said operations the reciprocation of the pump piston 63 by my fluid-pressure motor 56 pumps oil from the bottom of the well up through the pump 61, tubular extension 59, motor chamber 57 and outlet pipe 71 to the top of the well where the oil is discharged.

In Fig. 9 my invention is shown in multiple of two cylinders 42 and 80, and two pistons 44 and 81 in axial alignment one below the other. The cylinder 80 is of the same construction as the cylinder 42 except that the inner diameter of the upper end of the cylinder 80, above its head 47, is slightly enlarged and formed with an internal thread 82, which is screwed on the external thread 48 on the lower end of the cylinder 42. The lower end head 49 is threaded on the lower end of the cylinder 80 with the internal thread 51 of said head screwed on the external thread 48 on the lower end of said cylinder. The piston rod 45 extends downwardly from the piston 44 in the cylinder 42 through the packing box 47' in the upper end head 47 of the cylinder 80 and through said cylinder 80 and the packing box 52 in the lower end head 49 of said cylinder, and the lower end of said piston rod is coupled by the coupling 70 to the upper end of the connecting rod 67 of the pump 61, the pump barrel 62 being threaded at its upper end on the extension 59 on the lower end of the motor chamber 57, as here-

inbefore described. The piston 81 is secured on the tubular piston rod 45 in the cylinder 80, which tubular piston rod is provided with a port 83 below said piston 81 opening into said cylinder 80. A port 84 leads downwardly from the port 54 through the wall of the cylinder 42 and connects at its lower end with the upper end of a port 85, which leads downwardly from the upper end of the cylinder 80 through the wall of said cylinder and into the upper end of said cylinder below the upper end head 47 of said cylinder.

Air is admitted from the port 54 through ports 84 and 85 into the cylinder 80 above the piston 81, for forcing said piston downwardly, and air is permitted to escape from said cylinder 80 through the ports 85 and 84 to the port 54 on the upstroke of said piston, the air escaping through said port 54 as hereinbefore described.

Air is admitted through the piston rod 45 and port 83 into the cylinder 80 below the piston 81 to force said piston upwardly, and the air is permitted to escape from said cylinder through said port 83 and the piston rod 45, and from said piston rod, as hereinbefore described, on the downstroke of said piston 81.

I claim:

1. A fluid pressure motor including a valve housing, a valve head threaded in said housing, said valve head being provided with ports, a main valve and a pilot valve mounted on said valve head and controlling said ports, a power cylinder and piston, means for introducing fluid under pressure into said valve housing, means actuated by said power piston at the end of its upper stroke for positioning said valves to admit fluid under pressure from said valve housing through one of said ports leading into the upper end of said power cylinder for forcing said power piston down and for positioning said valves to permit escape of fluid under pressure from the lower end of said cylinder through one of said ports, and means actuated by said piston at the lower end of its stroke for positioning said valves to admit fluid under pressure from the valve housing through one of said ports to the lower end of said cylinder for forcing said piston upwardly, and for positioning said valves to permit the escape of fluid under pressure through one of said ports from the upper end of said cylinder.

2. A fluid pressure motor including a valve housing, a main valve and a pilot valve in said housing controlling ports, a cylinder, a reciprocative piston in said cylinder, a tubular piston rod extending through said piston and through the heads, respectively, of said cylinder, said piston rod being open at its upper end and closed at its lower end, but provided with a port below said piston communicating with said cylinder, means for introducing fluid under pressure into said valve housing, means actuated by said piston at the upper end of its stroke for positioning said valves to admit fluid under pressure from said valve housing through a port leading into the upper end of said cylinder for forcing said piston down and for positioning said valves to permit escape of fluid under pressure from the lower end of said cylinder through said port in said piston rod below said piston and through said tubular piston rod and one of the aforesaid ports, and means actuated by said piston at the lower end of its stroke for positioning said valves to admit fluid under pressure from the valve housing through one of the aforesaid ports and through said tubular piston rod and its port below said piston into the lower end of said cylinder for forc-

2,490,000

7

ing said piston upwardly, and for positioning said valves to permit escape of fluid under pressure through a port communicating with the upper end of said cylinder.
